UNITED STATES PATENT OFFICE.

BENJAMIN E. MEACHAM, OF LORAIN, OHIO, ASSIGNOR TO AMERICAN STOVE COMPANY,
OF ST. LOUIS, MISSOURI, A CORPORATION OF NEW JERSEY.

OVEN.

Application filed August 17, 1921. Serial No. 493,159.

To all whom it may concern:

Be it known that I, BENJAMIN E. MEACHAM, a citizen of the United States, residing at Lorain, in the county of Lorain and State of Ohio, have invented certain new and useful Improvements in Ovens, of which the following is a specification, reference being had therein to the accompanying drawing.

10 This invention relates to improvements in ovens, and more particularly to an improved oven construction in which the heating element is a gas burner.

My improved oven is designed for use in 15 domestic science schools, where the use to which it is put makes it desirable to have a number of small ovens operating at the same time, each individual oven being used by one of the pupils.

20 In my improved construction each of the individual ovens is contained in the one main oven and all of the ovens are in communication. The heat in the oven will be controlled by a regulator, such as is described in my Patent No. 1,334,776 of March 23rd, 1920, or a device of a similar nature. The regulator will be placed in the large oven and will control and regulate the heat for the several smaller ovens therein.

30 To maintain an even temperature in an oven of such large proportions where the heat is provided by a single burner and regulated by a single fuel control, there must be a free circulation of heat. The fuel ventilation must be properly located and of the right proportion, and the regulator is a very important factor as it controls the fuel supply in such a manner as not to cause excessive heat currents in certain parts of the 35 oven, which would make uneven temperatures unless the fire is properly controlled by the regulator.

To accomplish these ends and improved results, I have constructed my oven, burner 45 and regulator in a manner hereinafter described.

The primary object of my invention is to provide a main oven which contains a plurality of smaller supplemental ovens, whereby in the heat can be regulated and controlled to a desired temperature.

A further object of my invention is to provide a main oven which contains a plurality of supplemental ovens, whereby a plurality

of persons can use the oven, each person 55 having the use of one or more of the supplemental ovens.

A still further object of my invention is to provide an oven of the character described, which is cheap and simple to manufacture and efficient in operation.

Another object of my invention is to provide an oven containing a plurality of supplemental ovens in which there is a free circulation of heat, whereby a regulator can be 65 successfully used to regulate the oven temperature.

Other, further and improved objects and results of my improved oven will appear in the following description and accompanying drawings.

In the accompanying drawings—

Figure 1 is a view in side elevation of an oven constructed in accordance with my improved invention.

Fig. 2 is a vertical sectional view of the oven, as shown in Fig. 1.

Fig. 3 is a transverse sectional view taken on the line 3—3 of Fig. 2, looking in the direction indicated by arrow.

Fig. 4 is a transverse sectional view taken on the line 4—4 of Fig. 2, looking in the direction indicated by arrow, the regulator being shown in full line.

Fig. 5 is a view in detailed perspective 85 of one of the oven grate supports with the individual oven door-frame attached.

Fig. 6 is a vertical section view taken on the line 6—6 of Fig. 2, looking in the direction indicated by arrow.

Referring now to the drawings, in which like parts are designated throughout the description by similar reference numerals, my invention consists broadly of the main oven A, the supplemental individual ovens 95 or racks B, a fuel burner C, the heat and fuel regulator D and the oven-frame E, a more particular and concise description of which follows.

The main oven A is preferably oblong in 100 shape, although the shape may be altered as desired, and consists of the bottom 1, the end walls 2 and 3, the back 4, the front 5 and the top 6. The top, bottom, front and sides are preferably of flat sheet metal, as 105 shown, and are spot welded as at 7, or otherwise suitably fastened in the frame E, which is made preferably of channel iron, and the

corner uprights 8, which are elongated to form legs carrying the foot members 9, which support the oven above the floor 10.

As clearly appears in Figs. 2, 3 and 4 of the drawings, the oven is provided with an inner supplemental back 11, which extends the entire height of the oven and forms a flue 12, having an open bottom 13 and an opening 14, through the top 6 of the oven 10 into the flue collar 15.

The bottom 1 of the oven extends only from the front 5 to the flue wall 11 and is provided at its front and end edges with air openings 16, which aid the heat distribution 15 in the oven.

As clearly appears in Figs. 1 and 2 of the drawings, the front plate 5 of the oven is provided with a plurality of oven openings 17, and it is into these openings that the supplemental ovens or racks are placed.

The racks B consists of the horizontal frame members 18, preferably of angle iron, which carry at their outer ends the door-frame 19. The door-frame 19 is spot welded, as at 20, or otherwise fastened to the rack members 18, and the outer faces 21 of the door frame extend outwardly to overlap the front 5 of the oven, as at 22, and are bolted as at 23, or otherwise suitably fastened to the front 5 of the oven. The bolts 23 holding the door-frame 19 to the front of the oven are the only supports for the oven rack B, and the horizontal members 18 of the racks B are held in alignment and there properly positioned by means of the bands 24. The oven rack B is further provided with the horizontal U-shaped grill supports 25, for receiving the oven grills 26, which slide in and out upon 40 these grill supports.

The face 21 of the door-frame 19 is provided with the outstanding lugs 27 having openings 28 which receive and support in hinged relation the doors 30, by means of pins 29 and the lugs 31, which are carried by the door. The supplemental oven doors 30 are provided with the usual handles or knobs 32 and the doors with the glass 30^a to allow vision into the oven.

As clearly appears in the drawings, the main oven A carries six of the supplemental oven racks B, the oven racks being positioned two deep across the oven and comprise three tiers. It will, of course, be readily understood that the number of supplemental ovens can be varied to meet the desired use.

Below the bottom tier of the supplemental ovens B, is the burner space 33, in which the burner C extends across the back, sides and the front of the oven with the exception of the small space 34, where the ends 35 and 36 of the burner are in separated relation. The burner C is provided with 65 burner openings 37, these burner openings

being only in the front and side portions of the burner, as shown in Figure 3 of the drawings.

Supported on the front corner uprights or legs 8 of the oven A, by means of the brackets 38, or in some other suitable manner, is the gas supply conduit 39, which is in communication with a gas supply (not shown) and midway the length of the gas supply conduit 39 is a valve coupling 40 carrying the usual valve controlling handle 41. Connected to and supported above the valve coupling 40 is the heat and fuel regulator D. In communication with the lower portion of the heat and fuel regulator D is an air-mixer 42, which in turn is in communication with the gas pipe 43, which is in communication with the gas burner C, through the medium of the T-joint 44 or some other connection. 85

The upper end of the heat and fuel regulator D carries the inwardly extending thermostatic tube 45, which is in a position between the vertical tiers of supplemental oven members B, as clearly appears in the drawings. The heat and fuel regulator D carries a regulator wheel 46 for seating the thermostatic fuel and heat regulator to the desired adjustment for regulating the heat to the desired degree. I am not describing 95 the mechanism of the regulator D in particular, as this mechanism is covered by several patents granted to me, one of which is Patent No. 1,334,776, of March 23rd, 1920, and this thermostatic control could be constructed along the lines of any thermostatic control as known in the art. 100

Although I have described the burner C as a continuous burner encircling the bottom of the stove, with the exception of the 105 small space 34, it will be readily understood that the burner could be constructed in two U-shaped pieces, one end of the U-shaped pieces being connected by the T-joint 44, and the other end of the pieces being separated by the space 34. 110

The front 5 of the oven is provided with two observation openings 47, for observing the burner, and these openings are covered by the doors 48 pivoted as at 49. 115

As heretofore pointed out, to maintain an even temperature in an oven of such large proportions, with one burner and one fuel control, there must be a free circulation of heat and, therefore, the flue ventilation 120 must be properly located and of the right proportion.

To provide for this air circulation, I have first, as has been described, constructed the supplemental oven frames B of open construction and entirely supported from the front of the oven. To support the supplemental ovens from the oven walls or back would tend to obstruct the free passage of air in the main oven. In the bottom 1 of 125 130

the main oven I have provided the air openings 16 which are below the oven burner C throughout all of its portion which is provided with the burner openings 37. The 5 flue 12 of the oven has a free passage of air throughout its length, due to its open bottom 13 and its top opening 14, into the flue collar 15. To provide circulation of air and heat from the main oven into the oven 10 flue, I have provided a series of openings 50, and these openings are graduated as to numbers, as clearly appears in Fig. 6, and are in separated parallel relation.

The oven grills 26, which slide in the 15 supplemental ovens B as described, provide a means for supporting the food which will be put into the supplemental ovens for cooking. I have further provided two perforated plates 51, which will be supported and carried by the two lower supplemental ovens B, just above the oven burner C, as shown in Fig. 2 of the drawings. These perforated plates 51 are used for the 20 purpose of causing an even distribution of heat. The heat travels to a certain extent through these perforated plates, but the greater part of the heat will rise upwardly 25 through the space 52 at the edges of the plates and the supplemental oven racks B. From the foregoing it will be seen that I 30 have provided an oven in which there is a plurality of supplemental ovens or oven racks for individual or separate use, in which the heat is provided by a single 35 burner, the burner supplied by a single air-mixer and the heat and fuel controlled by a single automatic regulator.

Although I have not described in particular the heat regulator D, it will be understood that the regulator will be constructed in such a manner that when the regulator wheel 46 thereof is set at a predetermined 40 temperature, the regulator D will maintain this temperature in the main oven A by controlling the gas feed to the oven burner C.

Having thus described my invention, what I claim and desire to secure by Letters Patent is:—

1. A cooking or heating oven composed of 50 a plurality of supplemental ovens, each supplemental oven composed of an open framework and door frame supported only by the main oven front, separate doors for closing each oven frame, a gas burner for the oven, 55 and a heat and fuel regulator for regulating the temperature in the several ovens.

2. A cooking or heating oven having a plurality of supplemental ovens, the supplemental ovens composed of an open framework 60 carrying a door frame with door hinges, separate doors for closing each supplemental oven door frame, a burner for heating the ovens and an automatic regulator for controlling the temperature in the 65 ovens, for the purpose described.

3. A cooking or heating oven having a plurality of supplemental ovens arranged in tiers, a burner for heating the oven, and an automatic regulator situated at a point between the ovens, for the purpose of being in 70 both the horizontal and vertical air passage between the ovens for controlling the temperature in the supplementary ovens, for the purpose described.

4. A cooking or heating oven composed of 75 a plurality of supplemental ovens, each supplemental oven composed of an oven rack and door-frame, separate doors for closing each oven door-frame, a gas burner for the oven, and a heat and fuel regulator for regulating the temperature in the several ovens. 80

5. A cooking or heating oven having a plurality of supplemental ovens, a main oven flue behind the supplemental ovens, the supplemental ovens in communication with 85 each other and the oven flue, a burner chamber in communication with the main supplemental ovens only for heating them, and an automatic regulator for controlling the fuel inlet for the burner for regulating the 90 heat in the ovens.

6. A cooking or heating oven, having a plurality of supplemental oven-frames, a flue for the oven, a burner chamber for the oven separate from the flue and below the 95 supplemental oven-frames, a burner in the burner chamber, the supplemental oven-frames in communication with one another, and the burner chamber and oven flue, and an automatic regulator for regulating the 100 heat in the oven and the supplemental oven frames.

7. A cooking or heating oven having a plurality of supplemental ovens, a burner for heating the ovens, and an automatic regulator positioned between the supplemental 105 ovens for controlling the heat in the supplemental ovens, for the purpose described.

8. A cooking or heating oven having a plurality of supplemental ovens, the supplemental ovens composed of an open framework supported only by the main oven front, a burner for heating the ovens, and an automatic regulator for controlling the temperature 110 in the ovens, for the purpose described. 115

9. In a heating or cooking oven, a main oven having a plurality of supplemental oven-frames, the supplemental oven frames in communication to cause a free air-passage, a burner chamber below the oven frames in 120 communication therewith, a burner in the burner chamber, an oven flue having an open lower end out of communication with the burner chamber and in communication with the oven and the supplemental oven frames 125 above its open bottom, and an automatic regulator for controlling the temperature in the oven and the supplemental oven frames.

10. A cooking and heating oven having a plurality of supplemental ovens, a flue for 130

the main oven separate therefrom, the main oven flue open at its bottom and provided with an outlet opening at its top, a burner for the oven, the supplemental ovens in communication with each other and the oven flue, and an automatic regulator for controlling the temperature in the oven and its supplemental compartments.

11. A cooking or heating oven having a plurality of supplemental ovens, a flue for the main oven, a burner chamber below the ovens, a burner in the burner chamber, the supplemental ovens in communication with each other and the oven flue, air inlet openings into the burner chamber, the burner chamber in communication with the oven only, whereby an air current is caused to pass through the burner chamber into the oven and up the oven flue, and an automatic regulator controlling the temperature in the oven and its supplemental compartments.

12. A cooking or heating oven having a plurality of supplemental ovens, the supplemental ovens composed of an open framework supported only by the main oven front, a flue for the oven, the supplemental ovens in communication with each other and the oven flue, a burner chamber below the ovens, a burner in the burner chamber, the burner chamber in communication with the oven and provided with air inlet openings, and an automatic regulator for controlling the temperature in the ovens.

13. In a heating or cooking oven having a plurality of supplemental oven frames, the supplemental oven frames arranged in tiers and supported only by the oven front, and a burner for heating the ovens, for the purpose described.

14. In a heating or cooking oven having a plurality of supplemental oven frames, the supplemental oven frames arranged in tiers and supported only by the oven front, a burner chamber below the tiers of supplemental oven frames, a burner in the burner chamber, the burner chamber provided with air inlet openings and in communication with the oven, an oven flue extending the width and depth of the oven, and the oven in communication with the oven flue, for the purpose described.

15. In a heating or cooking oven having a plurality of supplemental oven frames, the supplemental oven frames arranged in tiers and supported only by the oven front, a burner chamber below the tiers of supplemental oven frames, a burner in the burner chamber, the burner chamber provided with

air inlet openings and in communication with the oven, an oven flue extending the width and depth of the oven, the oven in communication with the oven flue, and an automatic regulator for controlling the temperature in the oven.

16. A cooking or heating oven having a plurality of supplemental ovens, a flue for the main oven, the supplemental ovens in communication with each other and in communication with the oven flue by means of separated parallel rows of graduated openings, a burner chamber below the supplemental ovens, a burner in the burner chamber, the burner chamber provided with air openings below the burner and in communication at its top with the oven, and an automatic regulator for controlling and regulating the temperature in the oven.

17. A cooking or heating oven composed of a plurality of supplemental ovens arranged in tiers, the supplemental ovens in communication with one another, an oven flue in communication with the oven, a burner chamber below the supplemental ovens and provided with air inlet openings in its bottom and having an open top in communication with the ovens, a burner in the burner chamber, perforated heat deflecting plates carried by the lower tier of the supplemental ovens, and an automatic regulator for controlling the temperature in the ovens.

18. A cooking or heating oven having a plurality of supplemental ovens arranged in tiers, a burner for heating the ovens, and an automatic regulator situated between the vertical tiers of supplemental ovens for controlling the temperature in the ovens.

19. A cooking or heating oven having a plurality of supplemental ovens, the supplemental ovens composed of an open framework supported only by the main oven front, a flue for the ovens, the supplemental ovens in communication with each other and the oven flue, a burner for heating the ovens, and an automatic regulator for controlling the temperature in the ovens.

20. A cooking and heating oven having a plurality of supplemental ovens arranged in tiers, the supplemental ovens composed of an oven framework supported only by the main oven front, a burner for heating the ovens and an automatic regulator for controlling the temperature in the ovens.

In testimony whereof I hereunto affix my signature.

BENJAMIN E. MEACHAM.
